UNITED STATES PATENT OFFICE.

PEDER P. WESTBY, OF PETERBOROUGH, ONTARIO, CANADA.

PULP-SCREEN.

1,225,198.

Specification of Letters Patent.

Patented May 8, 1917.

Application filed June 9, 1913. Serial No. 772,568.

To all whom it may concern:

Be it known that I, PEDER P. WESTBY, subject of the King of Norway, residing at Peterborough, in the county of Peterborough, Province of Ontario, Canada, have invented certain new and useful Improvements in Pulp-Screens, of which the following is a specification.

My invention relates to paper making machinery and particularly to a pulp screen of the horizontal type, adapted to separate the fine fibrous or usable portion of the pulp from the coarse or unusable portion thereof.

The pulp screen forming the subject matter hereof is of that type employing an annular perforated screen, within which is mounted a revoluble distributor, operating to discharge the pulp by centrifugal tendency against and through the screen.

20 The object of the invention is to simplify the structure as well as the means and mode of operation of such machines, whereby they will not only be cheapened in construction, but will be more efficient in use, economical in operation, easily operated, readily accessible and unlikely to get out of repair.

25 A further object of the invention is to provide improved pulp feeding means whereby the rotary distributor will be supplied with the pulp equally throughout its circle of operation, whereby the entire screen surface may be utilized, thereby increasing the efficiency and capacity of the machine.

30 With the above primary and other incidental objects in view as will more fully appear in the specification, the invention consists of the features of construction, the parts and combinations thereof and the 35 mode of operation or their equivalents as herein after described and set forth in the claims.

40 Referring to the drawings, Figure 1 is a longitudinal, vertical, sectional view of the assembled machine. Fig. 2 is a transverse, vertical, sectional view on line $x-x$ of Fig. 1. Fig. 3 is a side elevation of the runner or distributor removed from the machine. Fig. 4 is a detail perspective view of the 45 screen supporting frame.

45 Like parts are indicated by similar characters of reference throughout the several views.

In constructing the machine there is em-

ployed a main frame or housing, comprising 55 oppositely disposed heads 1 and 2, connected at their upper portion by an interposed water supply chamber or conduit 3 and at the lower portion by a base member 4, in which is formed a receiving chamber 5 for 60 the screened pulp. This frame is provided with removable arcuate side members 6. These side members 6 may be secured in any desired manner, but in the drawings have been shown with dowels or studs 7 adapted 65 to engage sockets 8 upon the base member 4, and clamping members 9 located about the peripheries of the heads 1 and 2. These arcuate side members 6 in conjunction with the base member 4 form a substantially cylindrical housing or casing.

70 Removably supported in a concentric position within the casing or housing is an annular screen plate 10. This screen plate is 75 preferably divided into a plurality of arcuate sections, each supported upon a frame member comprising longitudinally disposed angle bars 11, connected by arcuate ribs 12. In order that the screen surface may be as little obstructed as possible, the arcuate ribs 80 12 of the supporting frame, are spaced away from the screen plate 10 as shown in Figs. 2 and 4. The end of the screen plate 10 is secured to the longitudinal angle bars 11, while the medial portions of the plate are 85 supported on bosses or lugs 13, projecting inward from the arcuate ribs 12.

80 In order to obviate the liability of breakage of the screen plate, due to the great pressure and strain to which it is subjected, 90 the central portions of the plate are rendered resilient or slightly yielding by forming the bosses or lugs 13 of rubber or other resilient material. It is to be understood that the resiliency of the screen plate is not 95 essential, but under certain conditions is desirable. Helical springs may be substituted for the rubber supports. In lieu of the resilient bosses 13, such bosses or supports may be formed integral with the arcuate ribs 12. 100 In the event that the bosses are formed of a resilient matter, a second resilient collar or washer 14 is preferably located on the inner side of the plate and the screen plate and collars are secured to the arcuate ribs 12 by means of a conical headed bolt 15. 105 In the event that solid, integral bosses 13 are employed, the second resilient collar

may be omitted and an ordinary metallic washer employed instead.

The conical head of the bolt 15 affords no place for the lodgment of the fibrous particles of pulp and serves to direct such portions of the pulp as may strike the bolt head onto the screen plate. The sectional screens and frames thus formed may be bolted one to the other, but are preferably secured by means of clamps 16 which engage the radial flanges of the angle bar 11. The screen plates and frames are supported upon annular flanges 17 upon the inner face of the heads 1 and 2. The lower portion of the heads 1 and 2 are provided with a second inward projecting flange 18 parallel with the flange 17 to form an intermediate groove within which the lower portion of the screen plate and frames engage. The sectional screen plate may be readily removed for inspection or replacement by the removal of the arcuate side members 6.

Journaled in suitable bearings 19 upon the heads 1 and 2, is a longitudinal shaft 20 carrying at one end a drive pulley 21. The shaft is located concentric with the screen plate and casing. Projecting inward from the head 2 and concentric with the shaft 20, is a pulp feeding chamber 22. This chamber comprises a circular stepped housing, the successive steps being concentric one with the other, and of sufficient difference in relative diameters to permit pulp feeding ports or orifices 23 in the transverse face of each successive step. By reference to Fig. 2, it will be seen that these ports or orifices 23 are of different relative sizes according to their height. It will be noted that the ports or orifices adjacent to the top of the feeding chamber are much larger than those at the bottom thereof. The pulp discharged within the screen plate will tend to settle or concentrate in the lower portion thereof, by the influence of gravity. This is to some extent compensated for, by the variation in the relative sizes in the ports, whereby a larger portion of the pulp will be discharged into the upper portion of the runner or distributor. The variation of the relative sizes of the port further compensates for the difference in pressure or head, under which the pulp is discharged to the higher and lower orifices.

There is formed in the head 2 an annular chamber or recess 24, communicating throughout its entire extent with the feeding chamber 22. This annular chamber or recess is provided with a pulp inlet 25. The pulp entering through the inlet 25, fills the annular recess 24 passing thence into the feeding chamber 22, from which it is discharged in a longitudinal or axial direction through the ports or orifices 23.

Secured upon the shaft 20 adjacent to the feeding chamber 22, is a hub 26, by which

are carried a plurality of radially disposed wings or vanes 27, forming the runner or distributor. These wings or vanes project radially to points adjacent to the annular screen plate and extend longitudinally throughout the width of the screen plate. The wings 27 overhang the feeding chamber 22 and are notched or recessed to correspond with the successive steps thereof. It is to be noted that each shoulder or offset 70 of the wings 27, extends inward beyond the orifices or ports 23 of the corresponding step of the feeding chamber 22. Inasmuch as the terminal port or orifices of the feeding chamber 22 are located closely adjacent to the shaft 20 and the intermediate space between successive wings or vanes is contracted in such close proximity to the hub 26, alternate wings are recessed or cut away adjacent to the last face or step of the feeding chamber, as shown at 75 28. At their outer end the wings or vanes 27 are connected one with the other by the annular rim 29, surrounding the feeding chamber 22. The wings are further supported and connected one with the other, by a transverse web 30, extending adjacent to the periphery of the runner or distributor, and substantially dividing the chamber of the machine into two compartments communicating one with the other through an annular opening about the periphery of the web, adjacent to the screen plate. Beyond the web 30 or in the second compartment the wings or vanes 27 are projected longitudinally as at 31, to overhang an inward annular projection 32 carried by the head 1 and provided with a peripheral flange 33 forming an annular channel 34. An outlet 35 for the tailings and coarse or unusable portions of the pulp, leads from this channel through the head 1.

A water supply conduit 36 leads to the water chamber 3 which is provided with a plurality of perforations adapted to discharge water in a spray upon the screen plate 10. A branch conduit 37 discharges a stream of water into the annular channel 34 to wash the tailings which are collected therein through the outlet 35.

The vanes 27, in addition to being radially disposed about the hub 26, are inclined somewhat to the axis of rotation as clearly shown in Fig. 3. The portion of the vanes 27 overhanging the feed chamber 22, is inclined in a forward direction while the extremity 31 is located slightly to the rearward, in relation to the direction of rotation. This causes the pulp discharged from the feed chamber 22, and which is carried outward or radially by centrifugal tendencies to gradually travel throughout the length of the vanes or wings. The finer and usable portions of the pulp will be discharged radially by centrifugal tendencies 115 120 125 130

against and through the perforated screen plate 10, into the annular chamber intermediate the screen plate and the cover section 6, through which chamber the screened pulp will pass to the receiving chamber 5, located in the base of the machine. From this chamber 5 the usable pulp is discharged through an outlet 38. The heavier and coarser portions of the pulp will gradually travel longitudinally upon the blade or wing, due to the inclination of such wings to the axis or rotation, while at the same time they will be moved outward under centrifugal tendencies. The unusable portions of the pulp will finally pass the periphery of the web 30 and will be discharged from the overhanging portion 31 of the vane into the annular channel 34, from which they will be flushed by water from the branch conduit 37 and finally discharged from the machine through the outlet 35. Located upon the rear side of each of the wings or vanes 27, adjacent to the edge thereof and parallel with the perforated screen plate 10, is a longitudinal flange or ledge 39, forming a recess 40 immediately beneath such ledge. As the runner or distributor rotates at a very high rate of speed, the tendency will be to form a partial vacuum within the recess 40 immediately back of each wing. This partial vacuum will create a suction upon the screen plate 10, tending to free it from the coarser particles which find lodgment thereon, drawing such particles away from the screen and again into the influence of the blades or vanes 27, upon which such particles will move longitudinally a limited distance before being again projected upon a screen. Thus such coarse particles are repeatedly projected from and returned to the influence of the wings or vanes until every particle of fine or usable material is separated therefrom by which time the coarse particles have traveled beyond the transverse web 30 and are deposited by the extension 31 in the waste or tailing channel 34.

It is to be noted that the outer edges of the ports 23 are flush with the walls of the feeding chamber 22. Thus there will be no obstruction to the free discharge of the pulp from the chamber and no tendency for the heavy portions of the pulp to settle within the feeding chamber 22 and remain therein. The offsets or shouldered portions of the wings or vanes by extending entirely across the ports 23 and closely adjacent thereto, create a suction upon the feeding chamber, which serves to draw the pulp through the ports and into the distributor. This action of the distributor assists in preventing the pulp settling within the feeding chamber and accelerates the flow of pulp therethrough.

From the above description it will be apparent that there is thus provided a device

of the character described, possessing the particular features of advantage before enumerated as desirable, but which obviously is susceptible of modification in its form, proportion, detail construction or arrangement of parts, without departing from the principle involved or sacrificing any of its advantages.

While in order to comply with the statute, the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended claims.

Having thus described my invention, I claim,

1. In a pulp screening machine, a casing, a screen member, a stepped feeding chamber projecting within the casing, said member having discharge ports in the transverse faces of succeeding steps, and a rotary distributor within the casing, the blades of which have stepped notches therein conforming to the contour of the feeding chamber which they overhang.

2. In a pulp screening machine, a casing, a screen member, a rotary distributor therein, a feeding chamber projecting within the casing in a position concentric with the distributor and having pulp discharge ports located in different vertical planes substantially perpendicular to the axis of rotation of the distributor.

3. In a pulp screening machine, a casing, a screen member, a rotary distributor, a feeding chamber projecting into the distributor in a position concentric therewith, said feeding chamber having pulp discharge orifices located at different distances from the axis of rotation of the distributor and in different planes substantially perpendicular thereto.

4. In a pulp screening machine, a casing, a screen member, a rotary distributor, a stepped feeding chamber projecting within the casing, said feeding chamber having pulp discharge ports in the transverse faces of succeeding steps.

5. In a pulp screening machine, a casing, a screen member, a circular feeding chamber projecting within the casing concentric with the distributor and having concentric pulp discharge ports in the transverse face thereof and coincident with the peripheral wall of the chamber, and a rotary distributor.

6. A pulp screening machine, a casing, a screen member, a recessed rotary distributor therein rotating on a horizontal axis, a concentric feeding chamber extending within

130

the recess of the distributor, and a series of ports in said feed chamber discharging in an axial direction and located in different planes throughout the axial length of the distributor.

7. In a pulp screening machine, a casing, a screen member, a rotary distributor therein rotating on a horizontal axis, a feeding chamber projecting within the casing having a plurality of arcuate pulp discharge ports therein, said ports varying in length according to their relative locations, the uppermost ports being larger than the lowermost ports.

8. In a pulp screening machine, a casing, a screen member, a rotary distributor therein, a stepped feeding chamber, a plurality of pulp inlet ports in the flat faces of each step, said ports of each step being of different areas in inverse proportion to the head or pressure under which the pulp is discharged through the individual ports.

9. In a pulp screening machine, a casing, a screen member, a stepped feeding chamber projecting within the casing, having pulp discharge ports located in different planes in the transverse faces thereof, and a rotary distributor recessed to conform to the contour of the feeding chamber.

10. In a pulp screening machine, a casing, a stepped feed chamber projecting within the casing having pulp discharge ports located in different planes in the transverse faces thereof, and a rotary distributor, having a plurality of substantially radially disposed blades, each of the blades being adapted to extend inward toward the axis of the distributor beyond the pulp discharge ports.

11. In a pulp screening machine, a casing, a screen member, pulp feeding means, a rotary distributor rotating on a horizontal axis comprising a plurality of substantially radially disposed blades, a transverse web connecting said blades and extending beyond the radial position of the pulp feeding means, said web dividing the casing into two compartments communicating one with the other about the periphery of the web, and an outlet conduit for tailings leading from one of the compartments.

12. In a pulp screening machine, a casing, a screen member, pulp feeding means, a rotary distributor comprising a plurality of substantially radially disposed blades inclined to the axis of rotation, a transverse web connecting said blades beyond the periphery of which said blades extend, said blades being correspondingly inclined at opposite sides of said web whereby heavy particles of pulp will be induced to travel toward said web beyond which they are deposited by the action of said blades.

13. In a pulp screening machine, a casing member, pulp feeding means, a rotary distributor within the casing and an inward ex-

ternal peripheral channel therein adapted to receive the tailings.

14. In a pulp screening machine, a casing, a screen member, pulp feeding means, an inward extension projecting from one end of the casing and concentric therewith and having a peripheral channel therein, and a rotary distributor having a plurality of substantially radially disposed blades overhanging the annular channel.

15. In a pulp screening machine, a casing, a screen member, pulp feeding means, a rotary distributor having a plurality of substantially radially disposed blades, each blade having on its rear side in relation with the direction of the rotation, a longitudinally disposed rib located adjacent to the edge of the blade.

16. In a pulp screening machine, a casing, a screen member, pulp feeding means, a rotary distributor having a plurality of substantially radially disposed blades and means to induce a suction upon the screen member in the rear of each blade to clear the screen member of adhering particles.

17. In a pulp screening machine, a casing, a screen member, a pulp feeding means, and a rotary distributor comprising a plurality of tangentially arranged blades, each blade being inclined to the axis of rotation.

18. In a pulp screening machine, a horizontally disposed cylindrical casing, a cylindrical screen member concentrically located within the casing, a horizontal shaft in axial alignment with the casing and screen member, a stepped circular horizontally disposed feeding chamber extending within the casing concentric with the shaft, said feeding chamber having pulp discharge orifices in the vertical faces of each succeeding step, and a rotary distributor carried on the shaft adjacent to the feeding chamber.

19. In a pulp screening machine, a horizontally disposed cylindrical casing, a cylindrical screen member concentrically located within the casing, a horizontal shaft in axial alignment with the casing and screen member, a stepped circular horizontally disposed feeding chamber extending within the casing concentric with the shaft, said feeding chamber having pulp discharge orifices in the vertical faces of each succeeding step, the area of those discharge orifices beneath the level of the shaft being less than that of those above the level of the shaft, and a rotary distributor carried by the shaft.

20. In a pulp screening machine, a horizontally disposed cylindrical casing, a cylindrical screen member concentrically located within the casing, a horizontal shaft in axial alignment with the casing and screen member, pulp feeding means leading to the casing, a rotary distributor carried on the shaft, a concentric annular extension projecting inward from one end of the cylindrical cas-

ing and having a peripheral flange forming a vertically disposed annular channel about said extension to receive the tailings.

21. In a pulp screening machine, a horizontally disposed casing, a cylindrical screen member concentrically located within the casing, a horizontal shaft in axial alignment with the casing and screen member, pulp feeding means leading to the casing, a rotary distributor carried by the shaft, comprising a plurality of substantially radially disposed blades, each blade being projected rearward adjacent to its edge to form a recessed rear face.
22. In a pulp screening machine, a casing, a cylindrical screen member therein, a supporting frame for the screen member, including annular ribs of different radius than that of the screen member, bosses located at several points upon the ribs with which the screen member is engaged and by which the screen member will be spaced away from the supporting ribs, and a rotary distributor.
23. In a pulp screening machine, a casing, a cylindrical screen member divided into

arcuate sections, a supporting frame for each of the sections comprising parallel arcuate ribs of different radius than that of the screen member, transverse bars connecting the arcuate ribs, and projections carried at spaced intervals by the arcuate ribs with which the screen member is engaged, whereby the screen will be spaced away from the ribs.

24. In a pulp screening machine, a casing, a cylindrical screen member divided into arcuate sections, a supporting frame for each of the sections comprising parallel arcuate ribs of different radius than that of the screen member, transverse bars connecting the arcuate ribs, and resilient supports interposed between the screen member and the ribs.

In testimony whereof, I have hereunto set my hand this 27th day of May, 1913.

PEDER P. WESTBY.
